UNITED STATES PATENT OFFICE.

WILLIAM A. SALTER, OF KANSAS CITY, MISSOURI.

PRINTING PRESS.

Application filed April 14, 1926. Serial No. 102,009.

This invention relates to printing presses of that class embodying a form-carrying reciprocating bed, and a revolving cylinder for making impressions, and more especially to a close-coupled one revolution and quick return press, and has for its object to produce a printing press that is simple and compact in its driving mechanism, capable of high speed and which will operate with 10 smoothness and without jar or jerk in its reciprocating motions.

Another object is to produce a printing press in which the gearing of the mechanism is constantly in mesh.

15 Another object is to produce a printing press in which the form-carrying bed travels at a very much higher rate of speed in its return, than it does during its printing stroke, and is given a long range of travel 20 with a relatively small cylinder diameter.

Another object is to produce a printing press in which the use of special devices or means, for the stopping and starting of the reciprocations of the form-carrying bed is 25 eliminated.

Another object is to produce a printing press that can be run in either direction, without injury to the mechanism.

With these general objects in view and 30 with others as may hereinafter appear, the invention consists in certain novel and peculiar features of construction and combinations of parts as hereinafter described and claimed;

35 And in order that it may be fully understood reference is to be had to the accompanying drawings, in which:—

Figure 1,—is a side elevation of a printing press embodying my invention, looking 40 at it from the right hand or driving side of the press.

Fig. 2,—is a vertical sectional end view 45 of the printing press to show the mechanical construction and operation of the members relatively to each other, looking at it from the back or rear end of the press.

Fig. 3,—is a sectional vertical side view 50 of the interior mechanism of the printing press, looking at it from the left hand side, and with the outside belt wheel and gears omitted.

Fig. 4,—is a diagrammatic view of positions of the driving mechanism of the reciprocating form-carrying bed, with its high 55 return speed, and showing where the type

bed and cylinder engage in the cycle of operation.

In the drawings, the main frame of the printing press 1, is journaled to carry the various shafts carrying the operating mechanism, provides the tracks on which the reciprocating bed works, and has two upwardly extending sides in which the cylinder is hung and provides support at the top for support of the sloping feed table, not 60 shown.

The driving power member 2, is mounted and rotates upon a fixed stud 31, that is securely fastened into the main bed or frame 1. This driving member 2 consists of a belt 70 wheel at its outer end receiving power from an electric motor or other source, and of a small gear at its inner end and which interengages with the cylinder gear 4 and the crank-shaft gear 7, causing them to both rotate in unison, they both being of the same diameter.

The cylinder gear 4, is rigidly mounted on the cylinder shaft 3, which rotates with it. This cylinder shaft 3 is journaled at either 80 end in bearings 28, 28 that are hung in the upwardly extending side rails of the main frame 1 and the cylinder shaft 3, has revolvably mounted upon it the printing cylinder 5. The cylinder driving lever 20, is 85 firmly attached to the cylinder shaft 3, and carries at its outer end the adjusting screw 21, that bears against the cross member 5' of the printing cylinder. The coiled spring 22 is mounted upon the cylinder shaft 3, 90 to which it is rigidly attached at one end, and the other end of this spring is attached or engages with the end of the cylinder 5 in such a way that the tension of the spring 22 causes the cross bar 5' to bear against 95 the adjusting screw 21, of the driving lever 20.

The impression cylinder 5 consists of two ends having bearings mounted upon the cylinder shaft 3, and joining the two ends 100 is the segmental peripheral impression platen 5" with a ribbed back for stiffness, and diametrically opposite the impression platen 5" is the cross bar 5', also connecting the two ends of the cylinder, and acting as a counterbalance and a driven member for the lever 20 to engage. The cylinder also carries paper grippers 24, which may be operated in any usual manner, but the operating mechanism of these grip- 110

pers is not shown as it is not a part of this invention and is old. The cylinder 5 also carries at one end and as an integral part thereof, a segmental gear 6, that is slightly longer than the length of the impression platen 5", and the curve of the diametral pitch line of this segmental gear 6, is approximately the same curve or circle, as the curve or circle of the impression face of the impression platen 5", and the function of this segmental gear 6 is hereinafter described.

The crank shaft gear 7, engages with the power member 2, and is rigidly mounted upon the crank shaft 8, that is journaled in the main frame 1. The crank shaft 8 has rigidly mounted integrally with it the crank 8 and pin 9, and the sliding bearing block 10 is mounted on the crank shaft pin 9 and engages with the slot 11' of the oscillating segmental gear 11. The oscillating segmental gear 11 is mounted on the shaft 23 as its fulcrum, and carries at its outer peripheral end a segmental gear that engages with the driving countershaft gear 13. It also has the radial slot 11' in which the sliding bearing block 10 operates for driving purposes and gives to it its oscillating motions. The shaft 23 is mounted in the main frame 1, and carries the oscillating segmental gear 11.

The reciprocating form-carrying bed 15 is carried back and forward in its operations on the rollers 26, 26, that travels in the tracks 27, 27, of the main frame 1. This reciprocating form-carrying bed 15, has as an integral part thereof driving racks 16, 16, that engage with the countershaft rack gears 14, 14; it also carries on its upper side the short rack 17 that engages with the segmental cylinder gear 6, and the inking plate 18.

The countershaft 12, is journaled in the main frame 1, and carries rigidly mounted upon it, countershaft rack gears 14, 14, engaging with the driving racks 16, 16 of the form carrying bed 15, and it also has rigidly mounted upon it the driving countershaft gear 13 engaging with the oscillating member 11.

The delivery rollers 25, the delivery fly fingers 32, and the inking rollers 19 are shown in Fig. 1, but the operating mechanism thereof is not shown, but any usual form may be used as this is old and does not constitute a part of this invention.

The cylinder shaft bearings 28, 28 are hung in the upwardly extending sides of the main frame 1, so that they may rotate in their seats, and the bearings for the cylinder shaft 3 are made eccentric to the outside circumference of them, so that when these cylinder shaft bearings 28, 28 are oscillated in their seats in the main frame, it is obvious 65 it raises and lowers the cylinder shaft 3,

and the impression cylinder it carries, relatively to the reciprocating form-carrying bed.

The throw-off lever 29 is hinged in the upwardly extending sides of the main frame 70 1, by the rod part 34, and has an integral part thereof in the short toggle levers 35. The eccentric shift levers 33 are rigidly attached to the cylinder shaft bearings 28, 28 and engage with rods 30, which in turn 75 engage with the short toggle levers 35, so that when the throw-off lever is moved backward the toggle opens drawing the eccentric shift levers backward and raising the impression cylinder platen from an impression point, relative to the form-carrying bed, and throwing the lever 29 forward locks the impression cylinder down.

In the operating of the oscillating segmental gear 11, that drives the reciprocating form-carrying bed, as illustrated in Fig. 4 the fulcrum of this segmental gear 11 being fixed in the shaft 23, and always in the same position to the crank shaft 8 which is at C, it is obvious that the crank pin 9 and its sliding bearing block 10 in their revolutions, use a great deal longer part of their circumferential travel in driving the oscillating segmental gear 11 in one direction, than they do in driving it in the reverse direction of movement. To this peculiarity of movement I utilize that part of the long circumferential travel of the crank pin 9 in driving the form-carrying bed during its printing stroke of travel, and the short section of the crank pin's circumferential travel, as from the lines B C to lines A C for the reverse movement. It also is obvious that when the crank pin 9 is at a position as indicated at the line A C in a steady 90 95 100 105 110 115 120 125 130 135 140 145 150 155 160 165 170 175 180 185 190 195 198 200 205 els without slippage with the form-carrying bed, this being allowed through the tension of the spring 22 and during which time the cross bar 5' moves away from the adjusting screw of the driving lever 20 and being at its greatest point away from the adjusting screw 21 when the crank pin 9 is at approximately point Z of its travel. From point Z of the crank pin's travel onward, the circumferential diameter of the pitch line of the gear 4 gradually overtakes the speed of travel of the form-carrying bed 15 until at a point approximately near Y they are traveling at the same rate of speed and at near which point the segmental gear 6 disengages from the rack 17.

In operation of the press, power being applied to the belt wheel, it causes the impression cylinder to rotate, and in unison with each revolution of the cylinder, through the crank shaft, and engaging members the form-carrying bed is caused to reciprocate in its travels, once for each revolution of the impression cylinder, the return of the form-carrying bed being much faster than the printing stroke.

From the above description it will be apparent that I have produced a printing press which embodies the features of advantage set forth as desirable in the statement of the object of the invention, and while I have illustrated and described the preferred embodiment of the invention, it is understood that I reserve the right to make such changes in the form, proportion, detail construction, and arrangement of parts, as properly fall within the spirit and scope of the appended claims.

I claim:

1. In a printing press, the combination of a frame, a continuously-driven power member, a revolving member driven by said power member and having a cylinder revolvably mounted thereon, a crank shaft engaging with the power member and through a radial slot driving an oscillating member, a reciprocatory bed, means operatively connected for transmitting power from the oscillating member to the reciprocatory bed, and a resilient member connecting the revolving member with the cylinder.

2. In an impression press, the combination of a frame, a continuously-driven power member, a printing cylinder driven by the power member, a reciprocatory bed, a crank shaft driven by the power member and driving an oscillating member, and a countershaft engaging with the oscillating member and the reciprocatory bed.

3. In a printing press, the combination of a frame, a continuously driven power member, a revolving member driven by the power member, an impression member mounted upon and flexibly connected with the revolving member, a reciprocatory bed driven by

the power member through operative means, movable journals carrying the revolving member and eccentrically mounted in the frame of the press.

4. In a printing press, the combination of a frame, a continuously-driven power member, a revolving member driven by the power member and having a cylinder revolvably mounted thereon, a crank shaft engaging with the power member and through a radial slot driving an oscillating member, a reciprocatory bed, means operatively connected for transmitting power from the oscillating member to the reciprocatory bed, a resilient connection between the cylinder and the revolving member, a movable journal carrying the revolving member and eccentrically mounted in the frame of the press.

5. In a printing press, the combination of a frame, a continuously-driven power member, a revolving member driven by the power member and having a cylinder revolvably mounted thereon, a crank shaft engaging with the power member and through a radial slot driving an oscillating member, a reciprocatory bed, a countershaft engaging with the reciprocatory bed and the oscillating member, and a resilient member connecting the cylinder with the revolving member.

6. In a printing press, the combination of a frame, a continuously-driven power member, a cylinder driven by the power member, a reciprocatory bed, a crank shaft driven by the power member, means for transmitting power from the crank shaft to the oscillating member, means for transmitting power from the oscillating member to the reciprocatory bed, and a segmental gear mounted on the cylinder that engages with a rack on the reciprocatory bed.

7. In a printing press, the combination of a frame, a continuously-driven power member, a revolving member driven by the power member and having a cylinder revolvably mounted thereon, a crank shaft engaging with the power member and through a crank pin driving an oscillating member, a reciprocatory bed, operated means for connecting the reciprocatory bed with the oscillating member, a segmental gear integral with the cylinder that engages with the reciprocatory bed, and a resilient member connecting the cylinder with the revolving member.

8. In a printing press, the combination of a frame, a continuously-driven power member, a revolving member driven by the power member and having a cylinder revolvably mounted thereon, a crank shaft engaging with the power member and through a crank pin and radial slot driving an oscillating member, a reciprocatory bed, a countershaft engaging with the reciprocatory bed and the oscillating member, a segmental gear integral with the cylinder that engages with a rack on the reciprocatory bed, and a resilient

member connecting the cylinder with the revolving member.

9. In a printing press, the combination of a frame, a continuously-driven power member, a revolving member driven by the power member and having an impression cylinder revolvably mounted upon it, a crank shaft driven by the power member, a reciprocatory bed, operative means engaging the

crank shaft and the reciprocatory bed, a rack on the reciprocatory bed, a segmental gear integral with the impression cylinder, that engages with the rack on the reciprocatory bed, and a resilient member connecting the impression cylinder with the revolving member.

In testimony whereof, I affix my signature.

WILLIAM A. SALTER.
